Application February 1, 1944, Serial No. 520,664

16 Claims. (Cl. 92—44)

1

A primary object of this invention is to provide an improved method and machine for producing paper, said machine and method affording excellent web formation of substantially any desired character under more positive and precise control and at speeds of operation materially in excess of those obtainable by known practicable methods and machines of the prior art.

Other and more specific objects, as well as the novel characteristics of the machine and of the method which contribute jointly to the functional improvement, will appear hereinafter.

In the attached drawings:

Figure 1 is a vertical sectional view of the wet end of a machine made in accordance with the invention;

Figure 2 is an enlarged detail view of a portion of the wet end of the machine shown in Figure 1;

Figure 3 is a sectional view on the line 3—3, Figure 2;

Figure 4 is an enlarged vertical sectional view illustrating certain details of the machine not shown in the preceding figures;

Figure 5 is a sectional view on the line 5—5, Figure 4;

Figure 6 is a fragmentary sectional view illustrating structural details of the breast roll and associated suction apparatus;

Figure 7 is an elevational view from the left hand end of Figure 6, and

Figures 8 and 9 are front elevational views of certain gauging and indicating devices constituting elements of the means for control and regulation of the machine, as hereinafter set forth.

Referring to the drawings, the machine comprises essentially a traveling forming wire 1 and a breast roll 2 about which the wire is trained in conventional manner. Dilute paper stock, in the form of the usual water suspension, is brought to the wire through an enclosed passage 3 which, contrary to the conventional practice in machines of the Fourdrinier type, delivers the stock to the wire within an area 4 wherein the wire still finds direct support upon the roll 2. Formation of the web upon the wire occurs almost entirely within this area 4, and accordingly the area will be referred to hereinafter as the forming zone. In effect the zone is defined by the terminal end of the passage 3 and is enclosed by

2

the upper and side walls of the passage. In the present instance, the passage 3 approaches the forming zone in a straight line tangential to the periphery of the roll and in alignment with the diverging line of the wire.

In order to provide for the required drainage of water of the stock suspension through the wire within the forming zone, and to facilitate removal of the drained waters, the roll 2 is constructed as shown in Figures 2 and 3. The outer peripheral portion of the cylinder is provided with a plurality of cells 5, the walls of which are formed by a series of radially disposed baffles or partitions 6. These partitions, in the present instance are set into and project from the cylindrical shell 7 of the roll and are disposed in the axial direction so that the cells 5 extend continuously substantially from one end of the roll to the other. The shell 7 is provided with apertures 8 which establish communication between the inner ends of the cells 5 and the interior of the roll, and it will be noted by reference to Figure 3 that these apertures 8 are arranged in closely set series extending longitudinally of the respective cells. Preferably the outer end of each of the apertures is counter sunk, as illustrated. Set into the outer edges of the partitions 6 is a wire 9 which extends in continuous convolutions from one end of the roll to the other; or a plurality of wires may be used each embracing the periphery of the roll. As shown in Figure 3, the outer edges of the wires 9 are flush with the outer edges of the partition 6 and these wires, with the partitions, form a backing for a wire 10 of coarse mesh which embraces the cylinder and forms a suitable support for the forming wire 1.

In the interior of the roll 2 and extending from one end of the roll to the other is a casing 11 which is mounted as hereinafter described for angular adjustment about the axis of the roll, as indicated by the arrows in Figure 4. One wall, 13, of this casing extends toward the inner surface of the shell 7 and carries a sealing element 14 which is resiliently pressed against the said surface by springs 15. The opposite wall 16 of the casing terminates in a curved surface 17 which defines a segment of a cylinder coaxial with the roll, and this surface 17 forms a seat for a bar 18 constituting an element of a structure 19 which

is supported on and secured to a shaft 12 and is adjustable angularly about the axis of the roll by rotary movement of said shaft. The structure 19 comprises a second bar 21 which, like the bar 18, extends over substantially the full length of the roll. Supported on and bridging the space between the bars 18 and 21 is a longitudinal member 22, this member being urged toward the inner surface of the shell 7, by springs 23, 23 and carrying spaced sealing elements 24 and 25 which bear against the said inner surface. The longitudinal member 22 is apertured, as indicated at 26 so that the space between the elements 24 and 25 at the inner surface of the shell 7 may communicate with the interior of the casing 11; and seated on an apertured flange 27 extending between the bars 18 and 21, is an apertured valve plate 28 which may be adjusted to regulate the effective opening through the flange 27.

As shown in Figure 6, the shell 7 has a hollow trunnion 7a which is journaled in roller bearings 7b in the fixed frame of the machine. The casing 11 is also provided with a hollow trunnion 11a which extends through the trunnion 7a and is journaled in roller bearings 11b, also in the fixed frame. The shaft 12 is rotatably supported in a cap 11c attached to the outer end of the casing 11, and projects somewhat beyond the cap, as shown. The casing 11 may be adjusted about the axis of the roll and with respect to the shell 7 by means of a worm and worm wheel 100, 101. The worm is attached to a shaft 102 journaled in the said frame, and this shaft carries a worm wheel 103 which meshes with a worm 104 also mounted on frame and adjustable through a hand wheel 105. The shaft 12 and the structure 19 are angularly adjustable about the roll axis and with respect to the casing 11 through an arm 106 on the outer end of the shaft. This arm is engaged on opposite sides respectively by set screws 107, 107 which are threaded through lugs 108, 108 on the cap 11c. By manipulating the screws, the position of the arm may be adjusted between and within limits imposed by the spacing of the said lugs. The valve 28 may be adjusted by way of a hand screw 109 threaded into the exposed end of the shaft 12, these elements being connected by transmission means including a lever 110 pivotally mounted at 111 on the structure 19 and connected to the valve; a second lever 112 pivotally supported at 113 on the shaft 12 and extending through a slot 114 in the shaft into operative engagement with the screw 109; and a rod 115 which connects the levers and carries a spring 116 acting to resiliently maintain the lever 112 against the end of the adjusting screw 109.

The interior of the casing 11 is connected through a port 29 and duct 30 with a suitable evacuator 32, see Figure 6, and the said duct contains a valve 31 so that regulated suction may be impressed upon the spaces between the sealing elements 14 and 24 and between the elements 24 and 25, this suction being impressed upon the portions of the inner surface of the shell which at the moment are exposed within said spaces. The suction thereby is impressed through the apertures 8 upon the associated cells 5 within the areas confined by the sealing elements. The strength of the suction in the primary area between the elements 14 and 24 may be regulated by adjustment of the valve 31, and the suction in the secondary area between the elements 24 and

25 may be independently regulated by means of the valve plate 28.

The total scope of the combined suction areas in the circumferential direction may be varied by adjustment of the structure 19 as described above. The position of the suction area with respect to the forming zone may be regulated by adjustment of the casing 11, also as described. In Figure 2, for example, the primary zone is shown as conforming substantially in position to the forming zone, but this relation could be changed by the aforesaid adjustment. If the casing were adjusted to the left, as viewed in Figure 2, the suction area could be made to act upon the cells 5 in advance of the forming zone, and if under these conditions substantial evacuation of the said cells were desired, in advance of the zone, such for example as a suitable apron overlying the wire, could be provided to seal the outer ends thereof within the area of approach.

20 That portion of the passage 3 which immediately adjoins the forming zone 4 extends in the present instance in a substantially horizontal direction and approximately tangential to the periphery of the roll 1 as previously set forth. 25 The upper wall of this portion of the passage 3 is formed by an adjustable section 33, see Figures 1, 4, and 5, which is slidably mounted in the fixed frame 34 of the machine for adjustment in a direction longitudinally of the passage 3, said section 33 being interlocked with frame through the medium of splines 35, one at each side of the frame 34, as shown in Figure 5. Adjustment of the section 33 may be effected by 30 actuation through a hand wheel 36 of a relatively fixed nut 37 on a threaded rod 38 attached to and projecting from the rear end of the said section. The hand wheel 36 is connected to a worm 39 which is journaled in a bracket 41 on the frame 34 and which meshes with a worm wheel on the nut 37. The bottom wall 42 and side walls 43 of this portion of the passage, see Fig. 5, are in the present instance fixed in the frame, but since the forming zone is defined by the terminal end of 45 the passage, an adjustment of the top wall section 33 will have the effect of regulating the length (in the direction of wire movement) of the forming zone. The actual length of the zone for any setting of the section 33 may be indicated 50 by a pointer 44 on the said section and a suitable related scale 45 on the frame, see Fig. 1.

Means is provided on the adjustable section 33 for varying the shape and cross-sectional area of the end portion of the passage 3 which immediately adjoins the forming zone 4. This means comprises, in the present instance, a pair of adjustable plates 46 and 47 forming parts of the upper wall of the passage. Each of the plates extends completely across the top of the passage 60. The edge of the plate 46 which is relatively remote to the forming zone is hinged to the body of the section 33, as indicated at 48, so as to provide for adjustment of the plate about an axis extending transversely of the passage 3 and parallel to the lower wall thereof. The hinge joint consists in the present instance of a rigid cylindrical rod 49 at the edge of the plate 46 which is supported in a semi-cylindrical socket 51 in the section 33 by means of a retaining bar 52, 65 said retaining bar engaging the surface of the rod 49 and forming with the latter a sealed joint in the top of the passage.

The plate 46 is supported at its other edge in a member 53 which is vertically adjustable in 70 the section 33. The member 53 which is shaped

as shown in Figures 4 and 5 and extends substantially the full width of the passage 3 between the side plates 43, is suspended from a plurality of screw threaded rods 54 which in turn are threaded into and depend from nuts journaled in fixed housings 55 at the top of the section 33. Each nut carries a worm wheel which is engaged by a worm 56 on a shaft 57 mounted for rotation in the top of the said section. Thus, by turning the shaft, through the medium, for example, of a wrench or hand wheel applied to the squared extremity 58, the member 53 may be elevated and lowered as required. As illustrated in Figure 5, the respective rods 54 are provided at their lower ends with oppositely projecting trunnions 59, 59 which fit into bores in blocks 61, 61 secured by cap screws 62 to the top of the member 53.

As shown in Figure 4, the near edge of the plate 47 is attached to the plate 46 and member 53 by means of a joint 63 corresponding to the joint 49—52 previously described, so that adjustment of the plate 46 necessarily entails an adjustment of the plate 47. The other transverse edge of the plate 47 is connected by means of a hinge joint 64 to the lower end of a member 65 which is suspended in the section 33 for vertical adjustment in a manner corresponding to the member 53 previously described. The joint 64 corresponds in principle to the joint 49—52, as illustrated in Figure 4. It will be apparent that by means of the adjustable sections 46 and 47 and the several associated joints the shape and cross-sectional area of the end portion of the passage 3 may be substantially modified as hereinafter more fully set forth.

Attached to and extending from the forward edge of the plate 47 and overlying the forming zone 4 is a flexible cover element 66. Attached to the top of the element 66 approximately at the midsection thereof is a rigid cylindrical rod 67; and a corresponding rod 68 is similarly secured to the outer edge of the element. These rods, which extend over the transverse width of the element, constitute elements of individual joints corresponding to the joint 64, and by these joints the cover element is attached to two vertically adjustable members 69 and 71 similar to the member 65 and in like manner suspended in the section 33. The details of the suspension, which corresponds also, to the suspension means for the member 53, are illustrated in Figure 4. Thus the threaded rods 72, which support the member 69 and which correspond to the rods 54 previously described, are supported in turn in nut 73 which is journaled in bearings 74 in a housing 75 at the top of the section 33. Each of the nuts comprises a worm wheel 76, and these wheels mesh with worms 77 on a shaft 78, see also Figure 5, by means of which the nuts may be simultaneously actuated to raise or lower the rods 72. The corresponding shafts for adjusting the members 65 and 71 are indicated at 79 and 81, respectively, in Fig. 4. The rod 68 may be jointed, if desired, so that the cover element 66, or the outer terminal edge thereof, may be made to curve slightly in the transverse direction if necessary.

The stream of dilute stock is delivered by way of the passage 3 to the forming zone at a velocity which may or may not be the same as the speed of the forming wire. Drainage of water through the wire within said zone results in the formation on the wire of a mat of the stock fibers, and pressure conditions in the stream within the forming area will depend on factors of velocity,

friction, and mat resistance. Regulated suction may be applied to the wire within the forming zone as previously set forth, this suction being sufficient to supplement the stream pressure and to drain through the wire within the forming zone all of the water of the stream with the exception of a minor portion thereof which is permitted to flow onto the wire as the latter leaves the zone. In Fourdrinier practice, it has been an accepted limitation that stock should be directed over the wire at a velocity substantially equal to, or somewhat below, the speed of the wire and that the hydraulic pressure of the stock behind the slice must be adjusted to the amount necessary to produce such velocities. By removing all but a minor portion, say 5%, of undrained stock suspension within the forming zone and directing this remaining small amount onto the wire in the direction of wire travel over but not impinging on the formed mat carried thereby, combined velocity and static pressures may be utilized which produce spouting velocities greatly exceeding the wire velocity without causing disruption of formation to any noticeable degree. Preferably such minor portion will be less than 10% of the suspension but not less than say 2%.

On the other hand the invention contemplates the provision of a suction source of such capacity as to make available vacuum sufficiently high to effect drainage of all or substantially all of the water from the stream within the forming zone when the static pressure of the stream has been reduced to a minimum or a negligible amount. While the use of suction as described above, either with or without hydraulic pressure, is generally desirable, the machine as constituted may also be operated in the absence of suction by utilizing hydraulic pressure alone to effect drainage into the periphery of the breast roll while the wire still finds support on the roll. In such operation the stream of water discharged from the roll, as hereinafter described, will underlie the upper reach of the wire more closely and may be diverted to the conventional saveall pan by a suitable deflector as illustrated in Figure 1.

The water drained through the wire within the forming zone passes into the cells 5 of the roll and these cells are made sufficiently deep to afford a capacity within the cellular peripheral portion of the roll capable of accommodating the water of the stream without displacement of any substantial portion thereof into the interior of the roll. The partitions 6 are preferably as thin as possible, consistent with the function of these elements to support the wire 1, so that in flowing into the peripheral portion of the roll, the stream may remain substantially intact, as illustrated in Figure 2. To this end also it is desirable that the depth of the cells shall not exceed the depth of the stream as it enters the forming area to an extent materially greater than is necessary to accommodate the water drained through the wire. Thus, the dilute stock remains substantially in the form of a single stream throughout the forming zone with the major portion of the fibers segregated to the upper side of the forming wire during its passage through said zone. As each of the cells 5 leaves the primary suction area, which is defined by the sealing elements 14 and 24, it comes immediately under the influence of the suction within the secondary area, defined by the sealing elements 24 and 25. The suction within the secondary area opposes centrifugal force tending to throw the water outwardly from the roll with-

out, however, drawing the water into the interior of the roll. The secondary area has been provided to permit adjustment of the vacuum for water retention independently of the vacuum for assisting drainage, but a single suction box may be used to accomplish both functions. At the point where the cells pass from the secondary suction zone centrifugal force may act without opposition to displace the water from the roll in a substantially tangential direction, as indicated in Figure 2, into the space between the upper and lower reaches of the wire and into a saveall pan of the type conventionally employed in Fourdrinier machines. In this operation, the fibers are continuously segregated from a major portion of the water of the stream by and on the wire entirely within the short length of the latter which is exposed within the forming zone, and at the terminal end of the forming zone the single stream of liquid is divided so that the major portion of the stream, from which the fibers have been withdrawn, may be directed in a path diverging from the fiber laden wire and from the minor portion of the stream which is directed over the top of the wire. This method of water removal permits the practical use of suction as a drainage means without the limitations on speed of operation which would arise were it necessary to dispose of the large volume of water through the suction means.

Incorporated in the machine with the afore-described forming means, is a highly flexible and accurate system of regulation. A means for regulating the shape and cross-sectional area of that portion of the passage 3 adjoining the forming zone, has been previously described, together with means for adjusting the contour and position of the cover element 66 which immediately overlies the forming zone. Means is also provided for regulating the volume of stock suspension passing through the passage 3 to the forming zone. In the present instance, the suspension is delivered to the passage by a pump 82, see Figure 8, and interposed between the pump and the passage 3 is the usual spreader which may be of conventional form and which functions to distribute the suspension from the discharge duct 83 of the pump with uniformity to the relatively wide and shallow passage 3 which, as previously set forth, extends across the full width of the machine. Regulation of the volume of the stock suspension delivered by the pump 82 may be effected in the present instance through a valve 84 in the duct 83, it being noted with reference to Figure 8 that the said duct contains a Venturi meter 85 whereby the volume, say in gallons per minute, may be indicated on a suitable control panel 86. This panel 86 may also contain the electrical controls 87 for adjustment of the valve 84 through the medium of a suitable electric motor 88 operatively connected to the movable element of the valve as illustrated. Conventional means is also provided for regulating the speed of the wire, and a tachometer for indicating the wire speed, say in feet per minute, is included at 89 on the panel 86. A further important element of the regulating system resides in the means illustrated in Figure 6 for regulating the suction at the forming zone. As previously set forth, the casing 11 is evacuated by a suitable pump 32, and in the suction line between the casing and the pump is a valve 31 by means of which the suction may be regulated as required. As previously set forth, the suction in the secondary area may

be independently regulated by means of the valve 28.

As a further element of the regulating system, illustrated in Figures 1 and 7, means is provided for accurately determining the velocity of the stock entering the forming area. It is apparent that the cross-sectional area of the passage 3 at the point of delivery to the forming zone varies directly with its depth. By providing a means for indicating the depth at this point, and having determined the volume of flow as outlined above, a quick calculating device may be used to accurately determine velocity or conversely the adjustments necessary to attain a desired velocity. Such indicating device may be operatively associated with one of the threaded rods which constitute the suspension means for the member 65, the rod being indicated in Figure 7 by the reference numeral 91. It will be apparent that the elevation of this rod will bear a fixed relation to the depth of the passage at the point where it joins the forming zone. Mounted at the top of the section 33, see Figure 7, is a bracket 92 to which is pivotally connected a bell crank lever 93. One arm of this lever seats upon the upper end of the rod 91 and the other end is connected to a pointer 94 which is also pivotally supported in the bracket. A spring 95 tends to retain the lever 93 in a position wherein the one arm seats solidly upon the threaded rod 91. The bracket also carries a dial 96 which in conjunction with the pointer 94, indicates the cross-section area of the passage at the stated position, say in square inches. It will be noted further that the contour of the cover element 66 over the forming zone may be modified as required through the members 69 and 71 to conform to the stock stream; and that the spacing of the outer edge of the cover member 66 from the wire 1 may also be regulated by adjustment of the member 71 as previously set forth. Since the wire at this point is supported directly on the roll, the space between the outer edge of the member 66 and the wire will remain substantially constant and the adjustment may be correspondingly close.

These elements of control, and the associated indicating devices, afford extremely flexible and precise regulation of the machine function, and in conjunction with the forming means previously described makes possible production of substantially any character of web at machine speeds materially in excess of those heretofore found practicable. The control means provides also for rapid and precise correction for possible variations in the freeness of the stock suspension or in other factors affecting the uniformity of the end product.

At the high speeds of which the machine is capable, say in excess of 2000 feet per minute, the suspension flows through the passage 3 at a velocity which in accordance with known hydraulic principles effects turbulence of a character tending to distribute the fibers uniformly and in random disposition in the stream. The section 97 of the passage immediately in advance of the forming zone is preferably adjusted to constant cross-sectional area and is of a length to permit the fibers to redistribute themselves after acceleration in the preceding contracting portion. In this section the constant high velocity is such as to insure turbulent flow of an order affording a completely random disposition of the fibers in the stream as it enters the forming area. When, therefore, the velocity of the stream and the

speed of the wire are the same the fibres are laid upon the wire in this same random arrangement and with such rapidity that the resulting paper web will be entirely free from coagulation and will exhibit the uniform strength in all directions characteristic of a "square" formation. By adjusting the machine so that the speed of the wire exceeds the delivery velocity of the stock stream a directional sheet may be obtained, and the necessary adjustments can be made rapidly and with extreme accuracy to afford any degree of directional effect desired. Accuracy of adjustment in this respect is facilitated by the fact that the directional effect is due almost entirely to the velocity differential between the stream and the wire so that adjustment is not complicated by directional effects arising from other causes, such for example as that which would result if the stock stream were accelerating as it approached the forming area.

As previously set forth, the object of this invention is to provide a method and machine for attaining excellent web formation at speeds in excess of those obtainable by known practicable methods and machines. To accomplish this object, means have been provided to subject a stream of stock suspension to pressure, suction, or simultaneous combination thereof without limitation and to any degree necessary to effect the drainage of substantially all of the stream in a forming zone during the time provided at any given speed of operation. Pressure and suction may be applied without limitation because: First, the forming wire is supported on a cylinder in the forming area and is, therefore, not subject to deformation and tensile stress, and second, the undrained portion of the stream is so small and is so directed that the mat of fibre carried by the wire is not appreciably disturbed regardless of the velocity at which this minor portion is spouted by the pressure within the forming area. At the high speeds afforded by this forced drainage the disposal of an extremely large volume of water is necessary and the method and means for handling this water as previously set forth is provided as an essential adjunct to the forming process. To afford the desired excellence of web formation, means have been provided to positively establish the stream delivery velocity and to control its relation to the velocity of the forming wire. The stream velocity itself has been utilized to disperse the fibres of the stream into random and uniform distribution and this dispersion is, therefore, enhanced rather than disturbed by increasing speeds of operation. Forced drainage is effective to quickly set these fibres into a mat and to thereby avoid coagulation and cross current irregularities which occur on the long forming area of the conventional Fourdrinier machine and are apparent in the finished web. By the elimination of operating speed as a limiting factor in formation and by the inclusion of precise operating controls this invention has provided the means and methods necessary to utilize vacuum-pressure formation to form an improved web of paper at speeds materially in excess of 2000 feet per minute.

We claim:

1. In a machine for forming paper webs, a rotary cylinder having an open cellular periphery, a traveling forming wire trained about the cylinder, means for flowing a stream of dilute paper stock to the periphery of the cylinder within the confines of a limited circumferential area of the latter, wherein the wire is operative

to separate the stock fibres from the water of said stream, means for draining substantially all of the water content of the stream into the said cellular periphery within the limits of said area, means to preclude outward discharge of any material part of the water from said periphery and to retain in said periphery a major part of the said drained water during a predetermined angular movement of the cylinder beyond the said area, and means for effecting discharge of the water thus retained outwardly from the periphery between the reaches of and remote to the wire.

2. In a machine for forming paper webs, a rotary cylinder, a traveling forming wire trained about the cylinder, means for draining the water from a suspension of paper stock through the wire within a longitudinal area thereof directly overlying the cylinder, an open cellular receptacle in the periphery of the cylinder extending over the entire circumference of the latter and adapted to receive and temporarily retain substantially all of the water thus drained, and means for effecting discharge of the said water outwardly from the periphery between the reaches of said wire.

3. In a machine for forming paper webs, a rotary cylinder, a traveling forming wire trained about the cylinder, means for delivering a stream of dilute paper stock to the wire within an enclosed area at the surface of the latter, said area lying against the cylinder and extending about a short circumferential area of the latter, and means for continuously draining substantially all of the water of said stream through the wire within the limits of said enclosed area, said delivery means comprising an enclosed passage having at the delivery end a longitudinal terminal section of substantially uniform cross-sectional area throughout, stock supply means for creating a high-velocity flow of the dilute stock through said passage to create uniform turbulent flow and resulting random disposition and uniform distribution of the stock fibres in the stream in the said enclosed area, and means in said cylinder for continuously conducting the drained water from the said area.

4. In a machine for forming paper webs, a suction roll, a traveling forming wire trained about said roll, an enclosed duct extending approximately tangentially to the roll and enclosing an area of the wire overlying the roll, the periphery of said roll being composed of open cells having a depth conforming substantially to the depth of the portion of the duct immediately adjoining the roll, means for applying suction to said open periphery from the interior of the roll, and means for maintaining suction on the open periphery substantially beyond the position where the wire leaves the roll.

5. In a machine for forming paper webs, a breast roll having an open cellular periphery, a traveling forming wire trained about the roll, means for delivering dilute paper stock to the wire, said means including a duct extending to and enclosing a longitudinal area of the wire against the roll so that within said area substantially all of the water delivered by the duct is directed through the wire and into the receptacle formed by said cellular periphery, said receptacle having sufficient capacity to retain for continuous withdrawal therein from said enclosed area substantially all of the water thus passing through the wire, and suction means for counteracting the centrifugal forces tending to throw the said water out of the receptacle and operative in conjunc-

tion with said forces to retain at least a major part of the water in the receptacle while passing from said zone for subsequent discharge outwardly from said receptacle at a point removed from the wire within the free space between the reaches of the latter.

6. In a machine for forming paper webs, a breast roll having an open cellular periphery, a traveling forming wire trained about the roll, means for delivering dilute paper stock to the wire, said means including a duct extending to and enclosing a longitudinal area of the wire against the roll so that within said area substantially all of the water delivered by the duct is directed through the wire and into the receptacle formed by said cellular periphery, said receptacle having sufficient capacity to retain for continuous withdrawal therein from said enclosed area substantially all of the water thus passing through the wire, and means for counteracting the centrifugal forces tending to throw the said water out of the receptacle and operative in conjunction with said forces to retain at least a major part of the water in the receptacle while passing from said area for subsequent discharge outwardly from said receptacle at a point removed from the wire within the free space between the reaches of the latter.

7. In a machine for forming paper webs, a breast roll having an open cellular periphery, a traveling forming wire trained about the roll, means for delivering dilute paper stock to the wire, said means including a duct extending to and enclosing a longitudinal area of the wire against the roll so that within said area substantially all of the water delivered by the duct is directed through the wire and into the receptacle formed by said cellular periphery, said receptacle having sufficient capacity to contain for continuous withdrawal therein from said area of a major part of the water thus directed through the wire, and means for applying suction to the receptacle from the interior of the roll, said means being operative in conjunction with the counteracting centrifugal forces to retain the said contained water in said receptacle while passing from the said enclosed area for subsequent discharge outwardly from the receptacle at a point removed from the wire within the free space between the reaches of the latter.

8. In a machine for forming paper webs, a breast roll having an open cellular periphery, a traveling forming wire trained about the roll, means for delivering dilute paper stock to the wire, said means including a duct extending to and enclosing a longitudinal area of the wire against the roll so that within said area substantially all of the water delivered by the duct is directed through the wire and into the receptacle formed by said cellular periphery, and suction means for counteracting the centrifugal forces tending to throw the said water out of the receptacle and constructed and arranged to operate in conjunction with said forces to retain the water in the receptacle, said suction means being operative in a segment of the circular path of the receptacle extending between the position where the wire leaves the said roll and a second position between the reaches of the wire and remote to the position first named and being inoperative in a segment following and immediately adjoining said second position so that in the latter segment the unbalanced centrifugal forces act to discharge the water outwardly from the receptacle.

9. In a machine for forming paper webs, a breast roll having an open cellular periphery, a traveling forming wire trained about the roll, means for delivering dilute paper stock to the wire, said means including a duct extending to and enclosing a longitudinal area of the wire against the roll so that within said area substantially all of the water delivered by the duct is directed through the wire and into the receptacle formed by said cellular periphery, means for applying suction to the receptacle within said area to augment the pressure in the duct tending to force the said water through the wire, and means for applying suction to the receptacle in the area extending from the said enclosed area to a terminal position between the reaches of and remote to the wire to counteract the centrifugal forces tending to throw said water out of the receptacle, said latter means being constructed and arranged to operate in conjunction with said forces to preclude outward discharge of any material part of the water contained in said receptacle and to retain a major portion of the water in the receptacle for subsequent outward discharge at said terminal position.

10. The method of removing water from a stock suspension to form a paper web which consists in continuously draining substantially all of the water from a stream of said suspension through a traveling forming wire into the open cellular periphery of a roll about which the wire is trained, accelerating said drainage by suction applied to said cells from the interior of the roll so as to complete the drainage within a small angular movement of the roll, retaining the major part of the drained water in the cells until the latter move to a position between the upper and lower reaches of the wire, and discharging the water outwardly from the cells at said position.

11. The method of forming paper webs which consists in delivering a stream of dilute paper stock to an enclosed zone at the surface of a traveling forming wire, draining water from said stream through the wire within said zone with resultant formation upon the wire of a mat of the stock fibres, discharging a residual portion of the stream over the mat as it leaves said zone substantially in the direction of travel of the mat and without impinging upon the latter, and limiting the amount of said discharge to less than 10% of the stream so as to avoid material modification of the mat irrespective of the velocity of said discharge relative to the speed of travel of the wire, said drainage being effected at least partially by static pressure in the stream, and said pressure being sufficient in conjunction with the initial velocity of the stream to produce a spouting velocity of said discharge greater than the speed of the wire.

12. The method of forming paper webs which consists in delivering a stream of dilute paper stock to an enclosed zone at the surface of a traveling forming wire, draining water from said stream through the wire within said zone with resultant formation upon the wire of a mat of the stock fibres, discharging a residual portion of the stream over the mat as it leaves said zone substantially in the direction of travel of the mat and without impinging upon the latter, and limiting the amount of said discharge to approximately 5% of the stream so as to avoid material modification of the mat irrespective of the velocity of said discharge relative to the speed of travel of the wire, said drainage being effected

at least partially by static pressure in the stream, and said pressure being sufficient in conjunction with the initial velocity of the stream to produce a spouting velocity of said discharge greater than the speed of the wire.

13. The method which consists in delivering a stream of dilute paper stock to an enclosed zone at the surface of a roll having an open cellular periphery, passing substantially all of the water of said stream through a forming wire trained about said roll and into the said peripheral cells, and retaining substantially all of the water so passed through the wire in the cells for removal from said zone and subsequent discharge outwardly from said cells to free space between the reaches of the wire.

14. The method which consists in delivering a stream of dilute paper stock to an enclosed zone at the surface of a roll having an open cellular periphery, passing substantially all of the water of said stream through a forming wire trained about said roll and into the said peripheral cells, retaining a major part of the water so passed through the wire in the cells for removal from said zone, and subsequently discharging the retained water outwardly from said cells to free space between the reaches of the wire.

15. A method according to claim 14 wherein the dilute stock is delivered to the roll in a stream of given depth, and wherein said stream depth is substantially maintained during passage through the wire and within the peripheral cells.

16. The method which consists in delivering a stream of dilute paper stock in a stream of given depth to the surface of a roll having an open cellular periphery, and passing substantially

all of the water of said stream through a forming wire trained about said roll and into the said peripheral cells while substantially maintaining said depth during and immediately following said passage.
